UNITED STATES PATENT OFFICE.

GEORGE DOBSON, OF PALISADES, COLORADO.

SKID FOR MINING-MACHINES.

1,298,304.

Specification of Letters Patent. Patented Mar. 25, 1919.

Application filed April 30, 1918. Serial No. 231,721.

To all whom it may concern:

Be it known that I, GEORGE DOBSON, a citizen of the United States, residing at Palisades, in the county of Mesa, State of Colorado, have invented certain new and useful Improvements in Skids for Mining-Machines; and I do hereby declare the following to be a full, clear, and exact description of the invention, such as will enable others skilled in the art to which it appertains to make and use the same.

The invention relates to a skid or runner, and more particularly to the class of adjustable skid attachments for coal cutting or mining machines.

The primary object of the invention is the provision of a skid of this character, wherein the same can be readily placed crosswise of the under frame of a coal cutting machine, such for example as that type known in the trade as the Goodman short wall mining machine, to enable the same to traverse a working place and to avoid any obstructions or obstacles which frequently happen to be in the way of the path of movement of the machine, such as boulders rising out of the working surface or floor in the mine, and particularly should the floor be of soft or clay formation.

Another object of the invention is the provision of a skid of this character wherein the coal cutting machine can be readily raised or lowered relative thereto to properly adjust the same for preventing the cutter bits thereof from going into the floor in the mine and especially when cutting in a pitching vein, and also eliminating the necessity of jacketing the machine for lifting the same over an obstruction or obstacle.

A further object of the invention is the provision of a skid of this character, wherein the cutting operation by the coal cutting machine can be executed with despatch, as all conditions ordinarily met with to obstruct the travel of the machine and the perfect working thereof will be overcome, the construction of this skid and the attachment thereof to the machine being of novel form to assure the positive and successful operation of said machine.

A still further object of the invention is the provision of a skid of this character which is comparatively simple in construction, readily and easily applied to a coal cutting machine, easily adjustable, thoroughly

reliable and efficient in its purpose, strong, durable and inexpensive to manufacture.

Other objects will be in part obvious and in part hereinafter pointed out.

The invention accordingly consists in the features of construction and arrangement of elements, the construction of which will be exemplified in the description hereinafter set forth and illustrated in the accompanying drawings, and the scope of the application of which will be indicated in the annexed claims.

In the accompanying drawings—

Figure 1 is a side elevation of a coal cutting machine in sumping position, showing the skid constructed in accordance with the invention applied thereto.

Fig. 2 is a fragmentary top plan view.

Fig. 3 is a rear elevation.

Fig. 4 is an enlarged vertical longitudinal sectional view through the skid taken through a part of the under frame of the machine.

Fig. 5 is a perspective view of the skid *per se*.

Fig. 6 is a detail plan view of the bracket for the skid detached from the under frame of the machine and looking toward the under face of the upper flange of said bracket.

Fig. 7 is a sectional view on the line 7—7 of Fig. 6.

Fig. 8 is a fragmentary elevation of the skid showing its relation to the bracket and the key engaged with its adjusting screw for turning the latter.

Similar reference characters indicate corresponding parts throughout the several views in the drawings.

Referring to the drawings in detail, A designates generally the coal cutting machine and B its under frame having mounted on one of its side sills or beams C the bracket for the skid, both being hereinafter fully described.

The bracket comprises an angle iron forming the vertical plate 10 and the horizontal plate 11 constituting angle flanges at right angles to each other. The vertical plate 10 is of less length than the horizontal plate 11 which is rounded as at 12 at one end, the vertical plate 10 being cutaway at opposite ends as at 13 and 14 and the end thereof at the cutaway portion 13 is beveled at 15 so as to avoid chafing of the steel cable of the coal

cutting machine when the bracket is mounted on the under frame B thereof in a manner presently described. The horizontal plate 11 of the bracket is formed with suitable holes 16 near the ends thereof for the fastening of the bracket in place.

The bolts 17 connecting under frame B to the body of the machine A are passed through the holes 16 in the plate 11 which 10 projects outwardly from the upper edge of the vertical plate 10 of the bracket when the latter is secured to the under frame and these bolts 17 securely fasten the said bracket in position on the under frame of the machine for the use of the skid hereinafter 15 fully described.

The skid comprises a flat plate 18 which is of the required length and width, preferably made from steel and constitutes a runner to be disposed crosswise beneath the under frame B of the machine A and is formed with an upwardly curled toe end 19, while spaced from this end and integral with or suitably secured to the plate 18 at its upper side is an L-shaped upright or support 20 which rises above the runner the required distance and is formed with a side bearing 21 near its upper end in which is threaded an adjustable jack screw 22 formed 25 with a hexagonally shaped head 23 on which is adapted to seat the horizontal plate 11 of the bracket on the under frame B of the machine. The head 23 of the screw 22 is formed with a series of holes 24 to receive a 30 pin or tool 25 constituting a lever for turning the screw to adjust the same in the bearing, the pin or tool being readily insertible in any of the holes and is removable therefrom.

40 On the under face of the plate 11 of the bracket are fixed diagonally disposed stop ribs or abutments 26 which are spaced apart the required distance and with which engages the head 23 of the jack screw 22 when 45 the skid is in position beneath the machine for use therewith. When the head 23 of the jack screw 22 is in engagement with any one of the abutments 26 and the machine A is in motion the skid will be prevented from 50 working along the side sill or beam C of the under frame B for the displacement of the skid when the machine is cutting across the face of the coal and the skid is sliding upon the working surface bed or floor of the mine. 55 In other words these ribs or abutments 26 on the bracket will hold the skid in proper position relative to the machine A to avoid displacement of said skid when traveling over the working place or floor in the mine. 60 during the cutting operation of the machine. The machine A can be raised and lowered

by adjusting the jack screw 22 relative to the skid so that when the machine is crossing a working place in its cutting operation it will pass over any obstacles or obstructions 65 and thereby eliminate the use of lifting jacks or the cleaning of the way of the machine which requires labor, as well as it retards the operation of the machine for the cutting of the coal with despatch.

70 From the foregoing it is thought that the construction and manner of use of the skid with the mining machine and its operation will be clearly understood, therefore a more extended explanation has been omitted.

75 What is claimed is:—

1. A skid of the character described, comprising a runner, means for securing it to the under frame of a coal mining machine, and raising and lowering means on the runner and engaged with the securing means to operatively hold the runner beneath the machine and to permit the raising and lowering of the latter relative to said runner.

80 2. A skid of the character described, comprising a runner, means for securing it to the under frame of a coal mining machine, raising and lowering means on the runner and engaged with the securing means to operatively hold the runner beneath the machine and to permit the raising and lowering of the latter relative to said runner, and means on the securing means and forming an abutment for the raising and lowering means to prevent displacement of the 95 runner.

90 3. The combination with a coal cutting machine having an under frame, of a bracket fixed to one side of the under frame and having a horizontal flange plate, a runner disposed beneath the under frame, an upright on the runner, a jack screw vertically supported on the upright and engageable with the flange plate, and an abutment on the flange plate for the jack screw.

100 4. The combination with a coal cutting machine having an under frame, of a bracket fixed to one side of the under frame and having a horizontal flange plate, a runner disposed beneath the under frame, an upright on the runner, a jack screw vertically supported on the upright and engageable with the flange plate, an abutment on the flange plate for the jack screw, and an upwardly curled toe on the advancing end of the 115 runner.

105 In testimony whereof, I affix my signature, in the presence of two witnesses.

GEORGE DOBSON.
